PAINT TUBE OPENER AND SQUEEZER

Elton E. McGilchrist, Salem, and Fletcher J. Pratt, Portland, Oreg.

Application April 28, 1952, Serial No. 284,728

3 Claims. (Cl. 222—81)

1

This invention relates in general to the mixing of paints and, more particularly, to the adding of colors in oil to a white or neutral paint or similar base.

Still more specifically this invention relates to means for removing the oil color from the collapsible tube in which such oil colors are customarily contained and for delivering the color as desired to the paint to be mixed.

Recently it has become the practice with paint dealers, who are required to meet a demand for a very wide variety of different colors and shades of paint, to mix the paint to order by adding one or more colors in oil to a white or neutral color paint until the desired color and shade of color are attained for the particular requirement. This practice not only increases the number of varieties and shades of colored paint with which the paint dealer is able to supply customers, but it eliminates the necessity for the dealer to keep on hand a large stock of many different colors of pre-mixed paint, some colors of which may not sell as rapidly as others. With this recent change of practice the paint dealer is obliged to keep on hand only a large stock of neutral paint or white paint together with the relatively small tubes of oil colors, which latter require much less storage space.

Oil colors used for paint are generally put up in collapsible tubes in a limited range of size. These tubes resemble the familiar containers in which tooth paste etc., are sold, except that the large circular discharge end of the collapsible tube in the case of oil paint colors is customarily formed without any discharge opening and must therefore be cut open when the oil color is to be removed from, or squeezed from, the tube. Heretofore the removal of oil colors from their collapsible tube containers has been done largely by hand and is regarded by paint dealers and store operators generally as a very messy and annoying operation.

An object of the present invention is to provide a device by means of which oil colors for paint can be dispensed from their collapsible tube containers as required without inconvenience to the operator engaged in the mixing of the colors in the paint and without any mess or soiling of the fingers of the operator.

A further and more specific object of the invention is to provide a convenient and adjustable device which can be used to open tubes of paint colors and to squeeze the contents from the same into the receptacle containing the paint which is being mixed.

2

An additional object of the invention is to provide a device of the character above indicated which will be simple and practical in construction, relatively inexpensive to manufacture, and the operation and maintenance of which will require only a minimum amount of care and attention.

We attain these objects and other incidental advantages with the paint tube opener and squeezer as hereinafter briefly described with reference to the accompanying drawings.

In the drawings:

Fig. 1 is a side elevation of our paint tube opener and squeezer, a large size paint tube (indicated in broken lines) being shown in the act of having the discharging end of the tube cut open preparatory to the squeezing of the contents from the tube;

Fig. 2 is a sectional elevation of the device and shows the paint tube inverted after the cutting of the end of the tube and in process of having the contents squeezed from the tube, the section corresponding to line 2—2 of Fig. 3;

Fig. 3 is a plan section of the device corresponding to line 3—3 of Fig. 2;

Fig. 4 is a fragmentary sectional elevation of the tube-cutting guide means taken on line 4—4 of Fig. 3;

Fig. 5 is a corresponding fragmentary sectional elevation of the tube-cutting guide means but illustrating the cutting guide in reversed position to accommodate a much smaller size paint color tube;

Fig. 6 is a fragmentary elevation on section line 6—6 of Fig. 3; and

Fig. 7 is a sectional elevation on line 7—7 of Fig. 3.

Referring first to Figs. 1 and 2, our paint tube opener and squeezer comprises a base 10, a standard 11, and an adjustably mounted bracket indicated in general by the reference character 12 on which the tube-cutting and squeezing means are carried. The standard 11 is formed with a central vertical slot 13 (Fig. 2) and the adjacent rear wall of the bracket 12 is formed with a lug 14 which extends into the slot 13 and is slidable therein. A bolt 15 extends through the bracket wall and through the center of the lug 14 and extends for some distance beyond the opposite face of the standard 11. A clamping nut 16 on the bolt 15 clamps the bracket 12 in desired adjusted position on the standard, the nut 16 preferably having an elongated arm 16' to provide a convenient finger hold when the clamping nut is to be tightened or loosened. The base 10

is preferably formed with two or more circular concentric recesses 17, 18 (Fig. 2) of progressively reduced diameters designed to fit the bottoms of paint cans of standard sizes, such as the large can C, in order to hold the can steady and in proper position for receiving the oil color squeezed from the paint color tube for mixing with the contents of the can.

The bracket 12 is adjustable as to height so that the paint color tubes of different sizes or length may be held directly above paint cans of different size and height and the contents of the tubes discharged centrally into the can as the tube is squeezed, without possibility of the squeezed-out oil color being deposited outside of the can.

The bracket 12 is formed with two spaced arm portions 12A and 12B (Fig. 3) extending in the same horizontal plane and parallel to each other. A shaft 19, extending through both of these arm portions and rotatably supported therein, carries a squeeze roller 20 which is secured to the shaft 19 and positioned between the arms. A small disc 21, having saw-like teeth on its periphery, is secured on one end of the shaft 19. A crank arm 22 is secured on the other end of the shaft 19 so as to enable the shaft 19, and with it the circular saw or cutter 21 and the squeeze roller 20, to be manually rotated when desired.

The arms 12A and 12B have identical longitudinal slots 23A and 23B respectively extending from a spaced distance beyond the bearings for the shaft 19 to the outer ends of these arms. An idler roller 24, of the same size as roller 20 and acting as a companion squeeze roller for the roller 20, has the ends of its shaft slidably and rotatably disposed in the slots 23A and 23B. A U-shaped cross head 26, slidably positioned in the slots 23A and 23B, has a concave groove in the tip of each side, and these grooves engage the corresponding ends of the shaft 25 of the idler roller 24 (see also Fig. 6). A bar 27, attached to the ends of the arms 12A and 12B, carries an adjusting screw 28 which engages the cross head 26 and thus, as apparent from Fig. 3, enables the position of the idler roller 24 to be adjusted with respect to the fixed roller 20. A pair of pins 29 and 30 hold the respective ends of the bar 27 removably secured in the ends of the arms 12A and 12B. The squeeze rollers 20 and 24 have their surfaces preferably knurled to aid them in taking a firm grip on the tube to be squeezed between them.

A cutting guide 31 (Figs. 1, 3, 4, 5 and 7) is mounted on the outside of the arm 12B of the bracket 12 by means of a screw 32. This screw 32 passes transversely through the approximate longitudinal center of the cutting guide. The shape of this cutting guide is shown most clearly in Figs. 1 and 3. The guide is formed with two oppositely-positioned sections 31A and 31B. A cylindrical channel 33 extends through the portion 31A. The wall of the other section 31B forms an incomplete wall around another channel 34 which is substantially cylindrical except for the incomplete wall portion where the outer face of the bracket arm 12B forms a portion of the channel wall. The channel 33 is of considerably smaller diameter than channel 34, but the axes of both channels are parallel, are spaced equal distances from the screw 32, and the screw 32 is so positioned with respect to the axis of the shaft 19 and cutter 21 that the axis of either channel will intersect the axis of the shaft 19

and cutter 21 when that channel is on the same side of the screw 32 as the shaft 19.

As indicated from Figs. 4 and 5, the cutting guide 31 may be rotated on the screw 32 when the screw 32 is loosened, so that either of the channels 33 or 34 may be positioned below the cutter 21, depending upon the diameter of the paint tube to be cut. In order to enable the edge of the cutter 21 to extend into the top of the smaller channel 33, when that channel of the cutting guide is being used, a pair of diametrically opposite slots 36 (Fig. 4) extend a short distance down into the channel wall. Also preferably the wall of the channel 33 is formed with an internal shoulder 35 at the top in order to prevent a small tube, when being cut, from inadvertently being thrust too far upwardly in its contact with the cutter which might then cause some of the contents of the tube to be thrown outwardly by the rotating cutter.

The manner in which our device is employed will be readily understood from the drawings. Assuming that a large size tube of paint color, such as that indicated by the broken lines in Fig. 1, is to be opened and the contents squeezed from the tube and discharged into the paint can C below the tube, the tube is first grasped in the hand of the operator and positioned as indicated in Fig. 1 with the discharge end up, and in this position the tube is inserted in the large channel 34 of the portion 31B of the cutting guide 31 until the tube end comes into contact with the cutter 21, which cutter the operator rotates with his other hand through the medium of the crank 22. As soon as a cut is made in the end of the tube (and this can readily be observed by the operator looking down on the large channel portion 31B of the cutting guide), the operator moves the tube down away from the cutter and cutting guide, reverses the position of the tube and inserts the flat end of the tube up between the squeeze rollers 20 and 24 as shown by the position of the tube T in Fig. 2. Further turning of the crank 22 by the operator then causes the tube to be drawn upwardly between the squeeze rollers and the contents of the tube to be squeezed from the cut or opened end of the tube (as shown in Fig. 2) and to be discharged into the can C in which the mixing is to take place.

If only small amounts of oil color are required and therefore small tubes are to be opened and squeezed, the cutting guide 31 preferably is reversed by loosening the screw 32 and rotating the cutting guide 180° from the position of Fig. 4 to the position of Fig. 5. The end of the small tube to be opened is then inserted up in channel 33 of the portion 31A of the guide 31. Since the channel 33 is much smaller than the channel 34 and the cutting of the end of the tube in the small channel is less easily observed by the operator, the small tube might be pressed up too far through the channel 33 causing the cutter 21 to pass down beyond the end of the tube. This could result in some of the oil color from the small tube being discharged into the channel 33, or on to the outside of the tube and also over the cutter 21. To prevent this an annular shoulder 35 extends up into channel 33 at the top and prevents the end of the tube from inadvertently being pushed up too far into engagement with the cutter. The slots 36 enable the cutter to extend down through the shoulder 35 just far enough to cut the desired

opening in the tube when the tube is in contact with the shoulder.

Thus the cutting guide, rotating cutter, and squeeze rollers cooperate in facilitating the opening and squeezing of the oil color tubes as the oil colors are required for mixing the desired color paint in the paint can which is set in place on the base in our device, and the opening of the paint color tubes and the squeezing of the material from them becomes a very simple, easily regulated and non-messy operation with the employment of our invention.

We claim:

1. In a paint color tube opener and squeezer of the character described, including a standard having a base for holding a paint can, a bracket adjustably mounted on the standard, and a pair of substantially horizontal squeeze rollers carried by the bracket, a shaft rotatably mounted on a fixed axis in said bracket, one of said rollers carried on said shaft, one end of said shaft extending beyond the side of said bracket, a cutter mounted on said end of said shaft beyond said bracket, a cutting guide mounted on said bracket adjacent said cutter for holding the round end of a paint color tube in position for engagement by said cutter, said guide having an open channel positioned below said cutter for the insertion of the end of the paint color tube, the axis of said channel being substantially perpendicular to and intersecting the axis of said cutter, and means for rotating said shaft and cutter.

2. In a paint color tube opener and squeezer of the character described, including a standard having a base for holding a paint can, a bracket adjustably mounted on the standard, and a pair of substantially horizontal squeeze rollers carried by the bracket, a shaft rotatably mounted on a fixed axis in said bracket, one of said rollers carried on said shaft, one end of said shaft extending beyond the side of said bracket, a disk-like cutter mounted on said end of said shaft beyond said bracket, a cutting guide mounted on said bracket adjacent said cutter for holding the round end of a paint color tube in position for engagement by said cutter, said guide having

40

45

a pair of open channels at opposite ends respectively of said guide, said channels being of different diameters to fit tubes of different size, said guide mounted on said side of said bracket for partial rotation to enable either of said channels to be brought into position below said cutter with the axis of such channel perpendicular to the axis of said cutter, and means for rotating said shaft and cutter.

3. In a paint color tube opener and squeezer of the character described, including a standard having a base for holding a paint can, a bracket adjustably mounted on the standard, and a pair of substantially horizontal squeeze rollers carried by the bracket, a shaft rotatably mounted on a fixed axis in said bracket, one of said rollers carried on said shaft, one end of said shaft extending beyond the side of said bracket, a disk-like cutter mounted on said end of said shaft beyond said bracket, a cutting guide mounted on said bracket adjacent said cutter for holding the round end of a paint color tube in position for engagement by said cutter, said guide having a pair of open channels at opposite ends respectively of said guide, said channels being of different diameters to fit tubes of different size, the axes of said channels in said guide being parallel to each other, said guide mounted on said side of said bracket for partial rotation to enable either of said channels to be brought into position below said cutter with the axis of such channel perpendicular to the axis of said cutter, an internal shoulder in said smaller channel to limit the extent to which the end of the paint color tube can be inserted in said smaller channel for contact with said cutter, and means for rotating said shaft and cutter.
